SHOWER BATH FIXTURE

Jacob W. Shook, Bellefonte, Pa., assignor to The
Titan Metal Manufacturing Company, Belle-
fonte, Pa., a corporation of Pennsylvania

Application December 14, 1938, Serial No. 245,742

1 Claim. (Cl. 299—141)

My invention relates to shower bath fixtures and more particularly to shower bath heads of the type disclosed in my co-pending application, Serial No. 229,596, filed September 12, 1938. In my said prior application a hollow perforated spherical cap or sprinkler member is mounted in the body portion of the sprinkler head for swiveling movement therein to thereby permit convenient direction of water flowing through the perforations at any desired angle to the axis of the head. Some difficulty has been experienced with my prior construction due to the clogging of the sprinkler perforations.

The object of the present invention is to so construct the swiveling member that it will be practically self cleaning or can be quickly and conveniently cleaned without disassembling any of the parts thereof.

Another object of the invention is to provide a self cleaning universally movable shower bath spray head which is of economical construction and easy to assemble.

Other objects and advantages of the invention will be apparent when the specification is considered with the accompanying drawing, in which:

Figure 1 is a sectional elevation of the shower head assembly;

Figure 2 is a bottom plan view of the shower head assembly;

Figure 3 is a top plan view of the sprayer head disassembled;

Figure 4 is a plan view of the gasket or packing gland;

Figure 5 is a plan view of the small split locking ring;

Figure 6 is a plan view of the large split locking ring;

Figure 7 is a fragmentary perspective of the spraying disk showing the notches or grooves therein;

Figure 8 is a fragmentary sectional elevation of the sprayer head assembly taken at right angles to Figure 1; and

Figure 9 is a detail view of the sprayer disk showing the inclination of the grooves therein.

Referring more particularly to the drawing, I denote in general a shower head constructed in accordance with my invention and comprising a hollow bell shaped body member 2 having a reduced internally threaded upper end 3 adapted to be connected to a water supply pipe, not shown. The open mouth 4 of the body 2 is sufficiently large to receive and house a semi-spherical sprayer or head member 5 through which water is sprayed in a manner presently under-

stood. An annular groove or recess 30 is formed in the inner wall of body 2, adjacent the lower edge thereof in which is seated a suitable gasket or packing gland or the like 31. The inner face of the gasket engages with the curved side wall of the sprayer head member 5 and forms a fluid tight seal between the head and body 2, thereby permitting free angular or swivel movement of the head without any danger of leakage between these parts.

The lower or outer end 6 of the spray head or member 5, projects outwardly a slight distance through the mouth 4 of body 2, and is provided with a water outlet opening 7. The wall 8 of this opening is beveled downwardly and outwardly at an angle about four degrees (4°) to the axis of body member 2, for the reception of a spraying disk 9, formed with a correspondingly shaped periphery 10. The peripheral surface 10 is formed with an equal number of equally spaced alternately arranged V-shaped grooves 11 and 12 of uniform depth throughout their entire length, the grooves 11 being inclined outwardly and downwardly at an angle of approximately two degrees (2°) from the longitudinal axis of the body member 2, and the grooves 11 being inclined outwardly and downwardly at an angle of approximately six degrees (6°) from the longitudinal axis of the body member 2. The difference in relative angularity between the two sets of grooves is indicated in Figure 9 of the drawing.

The spraying disk 9 is slidably mounted on a stem 13 which extends through a central opening 14 in the disk and is adjustably connected at its inner or upper threaded end 15 to the cross-head or spider 16 carried by the disk, the spider being formed with a threaded opening 17 for this purpose. A small split ring 18 and a shoulder 19 respectively confine the disk 9 slidably on the stem, and a larger split safety ring 20, seated in an annular groove 21 formed in the inner wall of the body 2 below the groove 30, serves to prevent the head 5 from dropping out of the body 2, should the gasket 31 become worn or otherwise damaged. The outer end of stem 13 is formed with a handle portion 22 for convenient manipulation of the head 5 and its disk member 9, relatively to the body 2, when the user desires to change the angular direction of the water flow through the discharge opening 7. The range of this adjustment is limited by means of an internal annular flange 23 formed on the inner face of the body 2 and adapted to be engaged by the upper peripheral edge 24 of sprayer

head 5 when the latter is moved in the manner indicated by the dotted lines of Figure 1. The range of movement is such that the grooves 11 and 12 will never be obstructed or closed by the 5 inner face or wall of the body member 2.

By virtue of the difference in inclination of the two sets of grooves 11 and 12 the water will be discharged in the form of inner and outer spaced cones 25 and 25' respectively, the inner cone flowing from the grooves 11 and the outer cone from the grooves 12, as illustrated in Figure 9, wherein the line 26 represents the slope of the peripheral face 10 of the disk 9 and the lines 27 and 28 indicate the slope or inclination of the grooves 11 10 and 12 respectively, relatively to the longitudinal 15 or vertical axis of the various parts of the shower head.

When the stem 13 is screwed home in the spider 16 sufficiently far to cause the peripheral face 10 20 of disk 9 to completely register with the wall of discharge opening 7, a shoulder 29 on the stem engages the spider and acts as an additional stop to further movement of the stem in this direction. It will also be noted that in this position of the 25 stem the disk 9 necessarily seats against the stem shoulder 19. If the stem is now unscrewed a distance represented by the space between the split ring 18 and the hub portion 32 of the disk 9, the periphery 10 of the latter will clear the 30 wall 8 of opening 7 and grooves 11 and 12 can be thoroughly flushed. If this flushing does not have the desired cleaning effect, the disk can be manually reciprocated on the stem within the limits

of the space previously mentioned or the grooves can be wiped off with a cloth or the like should this be necessary.

Having thus described my invention, what I claim is:

In a shower bath fixture, the combination with a hollow body member, a sprayer head mounted for pivotal movement in said hollow body and formed with an outlet opening, a stem extending through said outlet opening and fixed to said sprayer head for axial adjustment, a shoulder on said stem adapted to engage said sprayer head for limiting inward axial movement of said stem, and a disk slidably mounted on said stem and adapted to be moved to seated position in said outlet opening when said stem is axially adjusted in one direction, spaced means on said stem for limiting the inward and outward slidable adjustment of said disk on said stem, said first mentioned means comprising a split ring adjacent 20 said shoulder, and a handle on said stem, said disk having two sets of grooves in its periphery all of said grooves being of equal depth throughout their entire length, the grooves of both sets extending in the general direction of the axis of 25 the body member and being inclined at an angle to said axis and the said inclination of the grooves of one set being greater than said inclination of the grooves of the other set and means on said body adapted to be engaged by said sprayer head 30 for limiting the angular movement of said sprayer head.

JACOB W. SHOOK.
